UNITED STATES PATENT OFFICE.

AXEL A. SAWMAN, OF BROOKLYN, NEW YORK.

BOAT.

1,144,434.

Specification of Letters Patent. Patented June 29, 1915.

Application filed September 16, 1914. Serial No. 861,943.

To all whom it may concern:

Be it known that I, AXEL A. SAWMAN, a citizen of the United States, and a resident of the borough of Brooklyn, in the county 5 of Kings and State of New York, have invented certain new and useful Improvements in Boats, of which the following is a specification.

This invention relates to improvements in 10 boats, and especially life boats.

It is now usual to provide life boats with air tanks for buoyancy, which said tanks are fastened by nailing, riveting or other means, to the boat, and usually under the 15 seats. But when the air tanks are thus fastened it is difficult to remove them, and in the removal the tanks are liable to injury.

It is therefore the purpose of this invention to provide means for removably retaining said air tanks in proper position in the life boat, so that they can not accidentally shift their positions in the various emergencies of the use of the boat, but can be readily removed and replaced without injury to tanks or boat whenever it is desired 25 to inspect, remove, renew or replace said tanks.

The construction and arrangement of the parts of my said invention will be evident 30 from the following description, reference being had to the accompanying drawings, whereof—

Figure 1 is a longitudinal elevation and section of a life boat equipped with my invention; Fig. 2 is a cross section on a large 35 scale of a life boat of slightly different form, and showing a tank on one side of the boat in full lines, and indicating a tank being removed by dotted lines on the other 40 side of the boat. Fig. 3 is a perspective detail view showing the top plate, which normally prevents the removal of the securing rod.

A is a life boat and B seats along the 45 sides thereof, preferably supported by brackets b so that there is a clear space under said seats B in which to place the air

tanks T. Said tanks T are respectively properly shaped to fit under said seats B at their respective positions, and are arranged 50 end to end for practically the entire length of the boat, and so that it will not be possible to remove said tanks by endwise movement while the retaining rods C are in place. Said retaining rods C are vertical stiff rods, 55 preferably of metal, having their lower ends stepped in holes in foot blocks or boards e, and having their upper ends resting in through and through holes d in the outer part of said seats B; said holes d being normally covered by metal plates e, which are 60 screwed on the upper side of said seats B. Thus, when said plates e are in position, said rods C are retained in their normal position. There is a rod C for each tank T, said rods 65 being preferably located about midway between the ends of each said tank T. Thus, when said rods C are held in position by said plates e, said tanks T can not be removed; but when it is desired to remove any 70 tank, one of the screws of the proper plate e is unscrewed, and said plate e is then swung around to uncover its proper hole d, so that the desired rod C can be removed, and then 75 that tank can be readily withdrawn, and another tank put in its place, and so for any or all the tanks. Of course more than one rod for each tank could be used.

Now having described my improvements, I claim as my invention.

The combination of a boat, side seats thereof, having a space beneath them, a series of tanks substantially filling said space, removable rods adapted to prevent lateral removal of said tanks, and means to lock 85 said rods.

Signed at New York city in the county of New York, and State of New York, this 15th day of September, A. D. 1914.

AXEL A. SAWMAN.
